UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,367,774.

Specification of Letters Patent.

Patented Feb. 8, 1921.

Application filed April 13, 1918. Serial No. 228,417.

To all whom it may concern:

Be it known that I, JOSEPH C. FIELD, a citizen of the United States, residing at Orange, in the county of Essex, State of New Jersey, have invented certain new and useful Improvements in Signaling Systems, of which the following is a full, clear, concise, and exact description.

This invention relates to signaling systems and more particularly to selective signaling systems in which each of a plurality of stations connected with a pair of line wires is provided with a selectively operated signal control device.

15 An object of this invention is to provide in a system of this character improved means for communicating the correct time simultaneously to all stations connected with the line wires.

20 Another object of the invention is to provide a system of this character in which the time signals may be received without interfering with a conversation being carried on over the line wires.

25 In accordance with this invention, after the signal control devices at the various stations connected with the line wires have been conditioned for receiving time signals, the first energization of a time repeating relay

30 connected in a time circuit causes the operation of apparatus to connect a source of current with the line wires for causing the operation of the signaling devices at the several way-stations, and upon the second 35 energization of the time repeating relay, the apparatus operates in a different manner to connect current with the line wires for again causing the operation of the signaling devices. When selectively calling any station

40 connected with the line wires, the closure of a station contact establishes an operating circuit from the local signaling device, the association of which with the line wires is such that in operating, a return or answer

45 back signal is transmitted to the central station. When the selectively operated signal control devices are conditioned for receiving time signals, the association of the local signaling devices, when the time signals are 50 being received, is such as to effectively insulate the local signaling devices from the line wires, thereby preventing any disturbance on the line wires during the transmitting and receiving of time signals. In this man-

ner the reception of time signals will not 55 interfere with the carrying on of the conversation.

This invention will be more fully understood from the following description considered in connection with the accompanying drawings, wherein Figure 1 is a diagram of circuits and apparatus illustrating the invention; Fig. 2 shows an alternative form of control device for use at the central station; and Fig. 3 shows in detail how the 65 elongated holding pin of a selector is secured to the step-by-step element.

In Fig. 1 of the drawing, 5 and 6 designate a pair of line wires with which are associated a central or transmitting station A 70 and a plurality of way-stations, two of which, B and C, are shown. At each of the way-stations B and C is a selectively operated signal controlling device, each of which comprises in general a polarized operating 75 magnet 7, a step-by-step element 8 carrying a contact arm 9, and stationary contact elements 10 and 11. The step-by-step element 8 is mounted upon a shaft 55 and is held in the position shown by means of a 80 coiled spring 56, one end of which is secured to the shaft 55 and the other end of which is held in fixed position. In order that the contact-carrying element 8 may be advanced 85 step by step against the action of the coiled spring 56, there is mounted upon the shaft 55 a ratchet wheel 53 adapted to be engaged by a stepping pawl 13 and a holding pawl 54. The stepping pawl 13 is mounted upon the outer end of a pivoted rocker arm 50 90 while the holding pawl 54 is pivotally mounted and controlled by the rocker arm 50. The centrally pivoted armature 12 carries an S shaped arm 49 upon which are mounted pins 51 and 52, so positioned that 95 they impinge upon opposite sides of the rocker arm 50, whereby the stepping pawl 13 is caused to engage the ratchet wheel 53 upon each energization of the selector magnet 7. The holding pawl 54 is adapted to 100 maintain the ratchet wheel and contact-carrying element 8 in advanced position during a reversal of current through the windings of the selector magnet. Upon the cessation of the last stepping impulse of the 105 series which advance the element 8 into position where the contact arm 9 carried thereby engages the stationary contact 10, the piv-

oted armature 12 returns to its normal position, whereupon the spoon-ended holding spring 14 controlled by the rocker arm 50, engages the holding pin 15 carried by the 5 element 8 holding the element in contact-engaging position against the action of the coiled spring 56. When the contact arm 9 engages the stationary contact 10, which may be considered as the station contact, a 10 local circuit is completed through a vibrating bell 17. During the operation of the bell, a bridge of the line wires which includes impedance coils 20 and 21, resistance 23, condenser 24, the windings of vibrating bell 15 17, contact 10, contact arm 9, step-by-step element 8, pin 15 and holding spring 14, is alternately closed and opened to cause the transmission of an answer back signal to the central station A, where it is received in the 20 receiver 25. The element 8 is held in this contact-engaging position until further impulses are transmitted through the winding of the selector magnet to advance the element 8 to a position where upon the cessation of 25 the last of these impulses holding spring 14 will not engage the holding pin carried by the element 8. The coiled spring 56 thereupon returns the element 8 to normal position.

30 The stepping mechanism of the selector is also adapted in response to a predetermined number of alternating current impulses through the selector magnet to advance the contact-carrying element 8 into a position 35 where upon the cessation of the last impulse the spoon-ended holding spring 14 moves into engagement with the spoon-ended holding member 16 which (as shown in Fig. 3) is secured to but insulated from the lower 40 side of the contact-carrying element 8. In this predetermined advanced position of the contact-carrying element 8, the contact arm 9 is within one step of the contact 11, and the element 8 is held in this position 45 against the action of the coiled spring 56. The subsequent energization of the selector magnet 7 in response to an impulse of either polarity through the windings thereof, while the contact arm 9 is being held within one 50 step of the contact 11, causes the stepping mechanism to advance the contact-carrying member one step bringing contact arm 9 into engagement with contact 11. Upon the cessation of the energizing impulse, the centrally pivoted armature 12 returns to its normal position permitting the spoon-shaped end of the holding spring 14 to move into engagement with the elongated tail piece 55 of the holding member 16 and permitting 60 the stepping and holding pawls 13 and 54 to move out of engagement with the ratchet wheel 53. The coiled spring 56 thereupon returns the contact-carrying element 8 into its prior predetermined advanced position 65 with contact arm 9 within one step of the

contact 11 and the spoon-shaped ends of the holding spring 14 and member 16 in engagement. To return the contact-carrying element to its normal position, sufficient impulses must first be transmitted through the 70 windings of the selector magnet 7 to advance the element 8 such a distance that upon the cessation of the last impulse the spoon-shaped end of the holding spring will not engage the elongated tail piece of the holding member. The coiled spring 56 then, 75 after the movement of the stepping and holding pawls 13 and 54 out of engagement with the ratchet wheel 53, returns the contact-carrying element to its normal position. 80 Since the holding member 16 is insulated from the step-by-step element 8, no circuit across the line wires will be completed when the holding spring 14 engages the holding member 16, or when the contact arm 9 engages the stationary contact 11. 85

The selectively operated signaling device illustrated in the drawing which is of the type disclosed in my Patent No. 1,343,256, dated June 15, 1920, is provided with one 90 or more intermediate holding pins mounted on the element 8 which are variously positioned in different selectors, whereby for a predetermined code or combination of impulses transmitted, the station contact, 95 namely contact 10, of but one way-station connected with the line will be engaged by its associated contact arm 9. In fact, the contact arm at but one of the stations will be advanced as far as its station contact 10. 100 It will be understood that the same number of impulses are transmitted for selecting the various way-stations, the grouping of these impulses being different for the different stations. To advance the contact-carrying elements 8 of all stations into the position where they are held by the co-operating holding spring and member 14 and 16 with the contact arms 9 within one step of the 105 stationary contacts 11, one continuous 110 group of impulses is transmitted over the line circuit. The number of impulses of this group is, however, greater than the combined number of impulses of the groups comprising the code or combination of impulses required to selectively call the same 115 stations.

Connected to the line wires 5 and 6 at each of the way-stations, is an inductive bridge comprising the two impedance coils 120 20 and 21 and the windings of the selector magnets 7, included in serial relation with respect to each other.

Located at the central station A is a sending battery 30, the connection of which with 125 the line wires 5 and 6 is controlled by a relay 31 and a pole changing relay 32 in energizing circuits controlled by a sending key comprising contact spring 33 and contacts 34 and 35. When the sending key is set for 130

operation, contact spring 33 engages and remains in engagement with contact 34 during all of the time that the key is in operation, thereby to maintain relay 31 energized. 5 Contact spring 33 intermittently engages contact 35 during the operation of the key, thereby intermittently energizing the pole changing relay 32. In order to prevent the selecting impulses from the sending battery 10 from interfering with the proper operation of any telephone apparatus which may be connected with the line wires, there are provided retardation coils 36 and 37 in series with the line wires and condenser 38 and 15 resistance 39 in bridge thereof which cooperate to smooth out the sending impulses in a manner well understood.

There is also located at the sending station A a time repeating relay 40 connected in 20 a time circuit which controls a selector of precisely the same type as those shown at stations B and C. The windings of this selector are bridged by a condenser 29 of such capacity that the selector is rendered 25 non-responsive to very rapid closure and opening of the contacts of the repeating relay 40. Therefore, after the way-station apparatus has been conditioned for receiving time signals, should trouble develop on the 30 time circuit, causing the transmission of impulses in rapid succession over the time circuit, the non-response of the selector at station A therefore prevents the advancement of the way-station selectors. The adjustment 35 of this selector, however, is such that when the stepping pawl 13 has advanced the step-by-step element 8 one step, the contact arm 9 is in engagement with the stationary contact 10 and upon the cessation of the impulse 40 the magnet 7, the spoon-ended holding member 14 engages holding pin 15 to maintain the step-by-step element in contact engaging position against the action of the coiled spring 56. When the arms of a 45 double-pole double-throw switch 41 are in their left-hand position, relay 31 is energized and the pole changing relay 32 is controlled by contact arm 9 of the selector at station A, and when the switch arms are in 50 their right-hand position, relay 31 is controlled by contact spring 33 and contact 34, and the pole changing relay 32 by contact spring 33 and contact 35. The general construction of the selector at the central or 55 sending station "A" is similar to that of the selectors at the way-stations B and C. The selector at the sending station A is, however, not equipped with a spoon-ended holding member 16. The step-by-step element 8 of 60 this selector however, is so positioned that the movable contact 9 is normally within one step of the stationary contact 10.

In Fig. 2 there is shown a form of control device which may be employed at the central station A instead of the selector shown in

Fig. 1. This control device comprises an electromagnet 42, an armature 43 with which is connected a pawl 44 adapted to engage a ratchet wheel 45 mounted upon a shaft 46. A cam 47 is also fixed to the shaft 46 for controlling contacts 48 and 49. Upon the energization of the magnet 42, the armature 43 is attracted to cause the pawl 44 to engage the ratchet wheel 45 and rotates the shaft 46 and cam 47, thereby causing the end of the contact spring 48 to ride upon one of the elevations of the cam 47, and engage the contact 49. Contact spring 48 and contact 49 of Fig. 2 correspond to the contact arm 9 and the stationary contact 10 of the selector at station A. Condenser 29 in bridge of the winding of electromagnet 42 performs the same function as condenser 29 of Fig. 1.

When the system is in condition for selectively calling any of the way-stations 85 from the central station, the two arms of the double-pole double-throw switch 41 are in their right-hand position. To call any station, the sending key may be actuated to close contacts 33 and 34, thereby energizing 90 relay 31 to connect the sending battery 30 with the line wires, and the contacts 33 and 35 may then be engaged and disengaged through the intermediate contact 34 a number of times sufficient to cause the transmission of the requisite number of positive and negative impulses for advancing the step-by-step element of the desired station to circuit closing position to operate the vibrating bell thereat. In such contact engaging 100 position at the cessation of the last selecting impulse, the spoon-ended holding spring 14 engages holding pin 15 to maintain the step-by-step element in contact engaging position against the action of the coiled 105 spring 56.

When the way-stations are to be conditioned for simultaneously receiving time signals, the sending key is actuated to transmit the number of impulses required for 110 causing all selectors to advance their step-by-step elements 8 into a position where, upon the cessation of the last stepping impulse, the spoon-ended holding spring 14 engages the spoon-ended holding member 16 115 to maintain the step-by-step elements 8 in position with the contact arm 9 within one step of the stationary contacts 11. The attendant at station A may now move the two arms of the double-pole double-throw switch 120 from their right to left-hand position. Relay 31 is thereupon energized to connect the sending battery with the line wires 5 and 6. When the repeating relay 40 is energized in response to an impulse of current over the 125 time circuit, the local circuit including the magnet 7 of the selector at the central station A is closed, thereby causing the stepping pawl 13 to advance the step-by-step element 8 one step to cause the contact arm 9 130

to engage the stationary contact 10. The engagement of this contact 9 and the contact 10 causes the energization of the pole changing relay 32 over a circuit from the lower 5 terminal of battery 50 through contact arm 9, contact 10, lower arm of the double-pole double-throw switch 41, winding of the pole changing relay 32 to the upper terminal of battery 50. Pole changing relay 32 in operating 10 reverses the polarity of the sending battery 30 connected with the line wires, thereby transmitting an impulse of current through the magnets 7 of all selectors. Each way-station selector magnet is therefore 15 upon energized to cause its stepping pawl 13 to advance the step-by-step element 8 one step, whereby the contact arm 9 engages stationary contact 11 to close the circuit of vibrating bell 17. Upon the cessation of this 20 impulse over the line wires, due to the presence of the condensers 24 in series with the way-station magnets, the magnets 7 are de-energized whereupon the coiled springs 56 move the step-by-step elements back into position 25 with the spoon-ended holding spring 14 engaging the spoon-ended holding member 16. Each step-by-step element in returning to this position, causes the disengagement of its contact arm 9 and contact 30 11, thereby opening the operating circuit of the bell 17 controlled thereby. While the time signals are being received, the vibrating bells 17, 17 are not bridged across the line wires, and their operation will cause no 35 such disturbance on the line as there is when an answer-back signal is being transmitted. For a more detailed description of the operation 40 of the selectors at the way-stations when receiving time signals, reference may be had to my co-pending application, Serial No. 164,247, filed April 24, 1917. Upon the cessation of the impulse over the time circuit, repeating relay 40 releases its armature, whereupon the magnet 7 of the selector 45 at station A is de-energized. The spoon-ended holding spring 14 thereupon engages the holding pin 15 to maintain the step-by-step element 8 in position with the contact arm 9 in engagement with the contact 10. It will be understood therefore that the pole 50 changing relay 32 is maintained energized upon the cessation of the impulse over the time circuit.

The repeating relay 40 is again energized 55 in response to the next impulse over the time circuit, thereby again closing the energizing circuit for the magnet 7. The step-by-step element 8 at the central station A is advanced one step to cause the contact arm 9 to disengage the contact 10, thereby opening the energized circuit of the pole changing relay 32. Upon the de-energization of this pole changing relay 32, the polarity of the battery 30 connected with the line wires is 60 reversed, thereby transmitting another im-

pulse over the line wires to cause the selectors at all way-stations to advance their step-by-step elements one step, whereby the contact arms 9 temporarily engage the contacts 11 as before. Upon the cessation of the 70 impulse over the time circuit, repeating relay 40 is de-energized and magnets 7 of the selector at station A are also de-energized, whereupon the step-by-step element 8 is returned to normal position.

75

From this description it will be understood that the selector at the central station is advanced to the circuit closing position in response to the first impulse over the time circuit to cause the energization of the pole 80 changing relay, and that in response to the second impulse over the time circuit, the selector is advanced to open the energizing circuit of the pole changing relay, thereby permitting its de-energization. It will be seen, 85 therefore, that but one impulse of current is transmitted from the sending battery over the line wires in response to each impulse over the time circuit.

If the control device of Fig. 2 be substituted for the selector at station A, the first energization of the magnet 42 as a result of the first impulse over the time circuit causes the closure of contacts 48 and 49 and the energization of the pole changing relay 32, 90 while the second impulse over the time circuit causes the disengagement of contacts 48 and 49 and the de-energization of the pole changing relay 32. The two control devices, therefore, perform the same functions.

100

What is claimed is:

1. In a signaling system, in combination, a line circuit having a sending and a plurality of way-stations connected therewith, a selective signaling device connected with the 105 line circuit at each way-station, means at the sending station for preparing the signaling devices to receive a signal simultaneously at all way-stations, a time circuit, a relay in the time circuit, and means at the sending station responsive to an energization of the relay to connect with the line wires current of one polarity for operating all signaling devices, and in response to a succeeding energization of the relay to connect with the 110 line circuit current of opposite polarity for again operating all signaling devices.

2. In a signaling system, in combination, a line circuit having a sending and a plurality of way-stations connected therewith, a selective signaling device connected with the line circuit at each way-station, means at the sending station for preparing the signaling devices to receive a signal simultaneously at all way-stations, a time circuit, a relay in the 120 time circuit, and means at the sending station responsive to an energization of the relay to connect a source of current with the line circuit for operating all signaling devices and differently responsive to a succeed- 125 130

ing energization of the relay to connect the source of current with the line wires for operating all signaling devices.

3. In a signaling system, in combination, 5 a line circuit having a sending and a plurality of way-stations connected therewith, a selective signaling device connected with the line circuit at each way-station, means at the sending station for preparing the signal- 10 ing devices to receive a signal simultaneously at all way-stations, a time circuit, an electromagnetic switching device energized in response to each impulse over the time circuit, a source of current, and a pole 15 changing relay at the sending station energized upon the first response of the electromagnetic switching device to transmit over the line wires an impulse of one polarity from said source for causing the operation 20 of the signaling devices and deenergized upon the second response of the electromagnetic switching device to transmit over the line wires an impulse of opposite polarity from said source for again causing the op- 25 eration of the signaling devices.
4. In a signaling system, in combination, a line circuit having a sending and a plurality of way-stations connected therewith, an electromagnetic step-by-step selector at 30 each way station responsive to current impulses, a signaling device controlled by each selector, means at the sending station for causing the advancement of all selectors to a predetermined position, a time circuit, a 35 source of current, and means at the sending station actuated in response to an impulse

over the time circuit to transmit over the line wires an impulse of one polarity from said source and actuated in response to the succeeding impulse over the time circuit to 40 transmit over the line wires an impulse of opposite polarity from said source, the selectors at all way-stations advancing one step to momentarily operate the signaling devices in response to each impulse over the 45 line circuit.

5. In a signaling system, in combination, line wires having a sending and a plurality of way-stations connected therewith, an electromagnetic step-by-step selector at each 50 way-station responsive to current impulses, means at the sending station for advancing any selector into a first predetermined position and also for simultaneously advancing all selectors into a second predetermined po- 55 sition, a signaling device at each way-station operating when its selector is advanced into its first predetermined position and inter- mittently connected with the line wires during its operation, means rendered effective 60 by the operation of the signaling device to transmit a signal to the sending station, means at the sending station for causing a one step advancement of the selectors from the second predetermined position to operate 65 the signaling devices, and means to prevent the connection of the signaling devices with the line wires when operating after the one step advancement.

In witness whereof I hereunto subscribe 70 my name this 9th day of April, A. D. 1918.

JOSEPH C. FIELD.
